David E. Lain,
ATTORNEY.

UNITED STATES PATENT OFFICE

CHARLES T. O'HARA AND WILLIAM A. QUIRT, OF BELLINGHAM, WASHINGTON; SAID
O'HARA ASSIGNOR TO SAID QUIRT

FISHING-ROD REEL

Application filed October 29, 1928. Serial No. 315,647.

Our invention relates to improvements in fishing-rod reels, and has for an object to provide a reel the revolution of which is controllable by the application of the ball of the thumb or fore finger of the hand holding the rod to one of the reel flanges.

Another object of our improvement is to provide a reel for the stated purpose of extreme simplicity of structure, easy to make and unlikely to get out of order under the difficult conditions common to its use.

Other objects of our improvement will appear as the description proceeds.

We attain these and other objects of our improvements with the mechanism illustrated in the accompanying sheet of drawing, which forms a part of this specification, and in which Figure 1 is a plan view of our reel and Fig. 2 is a side elevation of Fig. 1 in section 20 on a medial vertical plane.

Similar characters refer to similar parts throughout the views, and certain parts are broken away to show other parts hidden thereby.

25 With more particular reference to the designated parts: Reel base 3 is curved laterally, as usual, to conform to the rod handle, not shown, and is fastened thereto with the usual slip rings, not shown.

30 A central boss 4 on the outside of base 3 has a tapped hole therethrough in which is engaged threaded end 6 of reel axle 5.

The body of axle 5 is of larger diameter than its threaded end 6 to provide a shoulder 35 to bear against boss 4 when said screw is driven home in the boss.

Hollow cylindrical windlass 7 has outer flange 8 and inner flange 9 fastened to the ends thereof to form the spool or drum of our 40 reel. Said flanges each have a central hole concentric with the axis of cylinder 7 through which is extended axle bolt 5 and said bolt is firmly screwed into boss 4 to cause its shoulder to bear on said boss with lower flange 9 45 also bearing thereon. Said axle bolt has head 55 to bear on outer flange 8, and thus is mounted the reel on said axle for revolution.

Flange 9 is preferably of larger diameter than flange 8 and preferably inclined outwardly and downward at its periphery pro-

viding the beveled extension 10 which is thus made conveniently accessible to the ball of the thumb or first finger of the hand holding the rod. The reel may be fastened either to the upper or lower side of the rod as the same is held in the hand. When fastened to the upper side of the rod the beveled edge 10 of the lower flange 9 is readily accessible to the thumb while, when the reel is on the lower side of the rod said flange periphery is readily accessible to the fore finger of said hand.

Preferably two handles 11, 11 are fastened to outer flange 8 for finger holds when winding in the line. Two handles being preferred because one will always be closely accessible when it is desired to wind in the line. In practice, with this simple form of reel, it is sometimes found convenient to retain the length of line paid out by taking a half hitch 70 therein on one of handles 11.

It also has been found that the manual braking means described is all that is needed to make this simple form of reel quite as useful as the more complex braking mechanism required in the ordinary reel.

When casting with a rather heavy rig or with chunk bait our reel unwinds so readily that a considerable length may pay out during the cast.

There are no hidden and delicate parts in 80 our reel to become clogged and injured by the presence of sand in its mechanism as quite often happens when using the well known form.

Having thus disclosed our invention, what 85 we claim as new therein and desire to secure by Letters Patent is,—

A fishing-rod reel consisting of a base for removable fastening to said rod longitudinally thereof, a reel axle fastened to said base operatively disposed radially with the axis of said rod, a reel spool mounted for revolution on said axle having an extended inner flange the rim of which is beveled outwardly toward 90 said base, and a handle fastened to the outer flange of said spool.

CHARLES T. O'HARA.
